THERMISTOR CIRCUIT

John H. Bollman, Rutherford, N. J., assignor to
 Bell Telephone Laboratories, Incorporated, New
 York, N. Y., a corporation of New York

Application December 26, 1941, Serial No. 424,455

8 Claims. (CL 219—19)

The present invention relates to circuits employing resistors of high temperature coefficient of resistance, commonly called thermistors.

More specifically, the invention relates to circuits using thermistors equipped with heaters for controlling their temperature in order to control their resistance. These are often referred to as indirectly heated thermistors in contradistinction to directly heated (or self-heated) thermistors which are heated in controlling degree by the RI^2 loss in the thermistor itself.

The heating coil is usually mounted with close thermal coupling to the thermistor element. In one type, the thermistor is a bead or block of some suitable substance having high temperature coefficient of resistance placed inside a glass tube and the heating coil is wound on the outside of the glass tube. It is found that in cases where there is a large difference of direct current potential between the thermistor element and heater winding, deterioration of the thermistor is liable to occur in time because of electrolysis through the glass or other insulation separating the thermistor and heater. Thermistors are usually semiconductors consisting of oxides, sulphides or other compounds subject to disintegration by electrolytic action and it is found that this action can occur through very high resistance insulation if a steady difference of potential is applied over a long period of time.

An object of the present invention is to protect against deterioration of this type by effectively reducing the difference of potential to a harmless value between the thermistor element and its heater winding.

This object is achieved in accordance with the invention by providing a leak path for direct current between the thermistor element and heat coil sufficient to reduce the steady drop of potential to a harmless value.

Reference will now be made to the accompanying drawing for a detailed description of one manner in which the invention may be practiced.

The single figure of the drawing is a schematic circuit diagram of a multiplex carrier repeater of the general type disclosed in United States patent to F. B. Anderson et al., 2,170,046, August 22, 1939, modified to incorporate the present invention. In the disclosure of that patent a three-stage amplifier is provided with a negative feedback connection and the gain of the amplifier is controlled by a variable impedance shunted across the feedback path, the value of 55

the impedance being controlled by a pilot wire regulator.

The present invention is embodied, in the present disclosure, in a similar amplifier in which the variable impedance for controlling the gain comprises a thermistor whose temperature is controlled by the pilot channel regulating circuit.

10 The amplifier itself is shown as comprising three stages 1, 2 and 3 with the input line or circuit at 4 coupled to the grid of stage 1 and the output line or circuit at 5 coupled to the plate of stage 3. The output stage includes in its output a bridge 6 with conjugate branches leading respectively to output transformer 7 and feedback potentiometer 8. The details of this bridge and of the rest of the amplifier circuit including interstages and other circuit elements have not been illustrated since they form no part of the present invention and they may be as disclosed, for example, in the Anderson et al. patent.

15 The feedback connection leads from an adjustable tap on potentiometer 8 via conductor 9 and stopping condenser 10 to the grid of stage 1. The cathodes are grounded through individual cathode networks 11, 12 and 13. For purposes of gain control (in addition to potentiometer 8) the thermistor 14 is connected between feedback conductor 9 and ground in series with 20 blocking condenser 15. (It is desirable to place condenser 15 on the "ground" side of the thermistor.) Impedance elements may be associated with the thermistor to modify its action as desired, such being indicated at 16 for example. 25 Plate voltage is supplied to the plate of stage 3 from battery 17 having its positive pole suitably connected to a point in the output bridge, as in the Anderson et al. disclosure.

30 The impedance of the thermistor shunt is controlled by supplying variable amounts of current to the heater winding 20 which has thermal coupling with the bead or element 14 but is insulated electrically therefrom, by a thin wall of glass or other suitable insulation. The insulation resistance may amount to the order of 100 megohms. The heating current might be controlled in any suitable manner, even by hand, but in a system such as that illustrated it is controlled from a pilot channel regulating circuit indicated at 21. This may be of the type shown, for example, in United States patent to Krist 2,246,307, June 17, 1941. It includes an input circuit 22 for deriving the pilot current from a suitable point in the circuit 5, together with filtering, amplifying and rectifying circuits for de-

veloping a heating current and supplying it through output transformer 23 to the circuit 24 leading to heater 20. The heating current may be 60-cycle alternating current of varying effective value determined by the pilot regulating circuit.

It will be noted that the thermistor 14 is at substantially the direct potential of the plate of the output stage, such as 130 volts, for example. Circuit 24 is shown having no direct conductive path to ground but it has unavoidable finite resistance to ground represented by the insulation resistance of transformer 23 and other associated circuit elements. This insulation resistance for direct current may be assumed to amount to several megohms. This and the insulation resistance of the thermistor glass insulation are found sufficiently low in practice to permit polarization of the glass to take place and a minute leakage current to flow across from the thermistor 14 to the heater 20 sufficient to cause deterioration in the thermistor after a sufficient period of service.

In accordance with the invention, this deterioration is prevented by connecting a leak resistor 25 of, for example, 1 megohm resistance between the thermistor 14 and heater 20. This resistance is low enough in comparison with the insulation resistance of the thermistor glass insulation and circuit 24 to ground so that the heater 20 is brought to nearly the same direct current potential as the thermistor 14 and leakage current through the insulating wall between 14 and 20 is substantially prevented. The resistance of 25 may be varied within rather wide limits and may be, instead of 1 megohm, for example, 100,000 ohms in the circuit illustrated.

The thermistor 14 with its heating winding 20 may, for illustration, be constructed as disclosed in United States patent application of G. L. Pearson Serial No. 236,307, filed July 25, 1939.

The invention is not limited to use with a feedback amplifier or with any type of amplifier but it is capable of use wherever a steady difference of potential is to be reduced to innocuous value between the thermistor element and heater.

What is claimed is:

1. An indirectly heated type thermistor, a heater therefor, means tending to maintain the thermistor at an unidirectional potential different from that of the heater and a leak resistance connected between the thermistor and the heater to reduce the potential difference to negligibly low value.

2. An indirectly heated thermistor, a heater therefor, means tending to maintain the thermistor resistance at unidirectional potential above that of the heater an amount sufficient to deleteriously affect the thermistor resistance, and means for raising the steady potential of the heater with respect to that of the thermistor resistance sufficiently to materially reduce the deleterious effect of steady potential difference between the thermistor resistance and the heater comprising a resistance connected between the thermistor element and the heater having a magnitude small compared to the minimum operating magnitude of the insulation resistance between the thermistor and the heater.

3. An indirectly heated thermistor, a heating

element therefor, means maintaining the thermistor at unidirectional potential above ground, and a resistance connected between the thermistor and the heating element having a magnitude small compared to the minimum operating magnitude of the insulation resistance between the thermistor and the heating element, the insulation resistance between the heating element and ground having an order of magnitude at least as large as said resistance connected between the thermistor and the heating element.

4. An indirectly heated thermistor, a heating element therefor, means maintaining the thermistor at unidirectional potential above ground, and a resistance connected between the thermistor and the heating element having a magnitude small compared to the minimum operating magnitude of the insulation resistance between the thermistor and the heating element and large compared to the magnitude of the resistance interposed by said means between said thermistor and ground.

5. An amplifier comprising a space discharge device, a space current supply source for said device, an indirectly heated type thermistor, a heating element therefor, a negative feedback path for said amplifier including the thermistor, means for electrically insulating the thermistor heating element from ground, means including a portion of said path conductively connecting a point of positive potential on said source to the thermistor resistance and maintaining the thermistor resistance at unidirectional potential above ground, and a resistance of the order of a megohm connected between the thermistor and the heating element.

6. A thermistor comprising a thermistor resistance having a large temperature coefficient of resistance, a heating element therefor, solid heat conducting electrical insulating material interposed between and in contact with said resistance and said heating element, and a resistance of the order of a megohm connecting said thermistor resistance and said heating element.

7. The combination with an indirectly heated thermistor having heat conducting solid electrical insulation between and in contact with the thermistor resistance and the heating element, of means maintaining the thermistor resistance at an unidirectional potential above ground, and means for maintaining the heating element at substantially the same average potential as the thermistor resistance.

8. The combination with a thermistor device comprising a temperature-dependent resistance and a heating element therefor, of means tending to maintain said temperature-dependent resistance at unidirectional potential sufficiently above that of said heating element to result in deterioration of said temperature-dependent resistance, and means for maintaining the unidirectional voltage between said temperature-dependent resistance and said heating element at innocuous value comprising a leak resistance connected between said temperature-dependent resistance and said heating element.

JOHN H. BOLLMAN.
